UNITED STATES PATENT OFFICE.

WILLIAM G. PATRIDIS, OF PITTSBURGH, PENNSYLVANIA.

CLIP FOR SECURING SHEET-METAL PLATES.

1,251,274.

Specification of Letters Patent. Patented Dec. 25, 1917.

Application filed August 1, 1916. Serial No. 112,514.

To all whom it may concern:

Be it known that I, WILLIAM G. PATRIDIS, a subject of the Kingdom of Greece, and resident of Pittsburgh, in the county of Allegheny and State of Pennsylvania, have invented a new and useful Improvement in Clips for Securing Sheet-Metal Plates; and I do hereby declare the following to be a full, clear, and exact description thereof.

10 My invention relates to clips for securing sheet metal plates, and has special reference to the devices for attaching the metallic sheets together and in place for forming the roof.

15 Heretofore, in the usual formation of these corrugated sheet metal roofs, the sheets were held in place on each side of their overlapping portions by means of sheet metal bands or strips, which are bent around 20 and under the lower flange of the supporting channels or bars, while the ends of such bands are bent against the under faces of said sheets and such ends and sheets are riveted together beyond said overlapping 25 portions. In this form a man on the roof and one underneath is required for connecting the sheets, and by reason of the bands extending around the supporting bars it was exceedingly difficult to paint the under side 30 of the roof when required, by reason of such bands interfering therewith.

The object of my invention is to overcome these objections and to provide a simple, cheap and efficient form of a clip, which 35 will enable the metal sheets forming a roof to be easily and quickly attached to the same, and one which will be supported and carried by the roof supports or channels generally employed, so as to be in position 40 for being readily and conveniently held for connecting such sheets thereto.

To these ends my invention consists, generally stated, in the novel arrangement, combination and construction of parts, as 45 hereinafter more specifically set forth and described and particularly pointed out in the claim.

To enable others skilled in the art to which my invention appertains, to construct 50 and use my invention, I will describe the same more fully, referring to the accompanying drawing in which:—

Figure 1 is a plan view, showing a portion of a roof having my invention applied 55 thereto;

Fig. 2 is a vertical section of the same on the line 2—2 of Fig. 1;

Fig. 3 is an enlarged detail sectional view, similar to Fig. 2, and showing a portion of the roof; and

Fig. 4 is a perspective view of one of the clips employed.

Like symbols of reference herein indicate like parts in each of the figures of the drawing.

As illustrated in the drawing the roof is shown at *a* which is composed of the usual corrugated metal sheets 1, the vertically disposed channels or supporting bars 2 for the same and the attaching clip 3, formed of metal strips for connecting the sheets 1 together for holding the same in place.

The clips 3 are of U-shaped form to provide for the legs 4 and 5 thereon, with the leg 4 longer than the leg 5 and provided 75 with a hole 6 within the same adjacent to the end of the short leg 5. Within the hole 6 and carried by the same is a rivet or staple 7, which fits loosely within such hole by its shank 8 and is provided with the usual head 80 9 on the end of the shank adjacent to the end of the short leg 5. The opposite end of the shank 8 is slightly tapered outwardly as at 10 to form a sufficient head 11 thereon to hold the rivet or staple 7 within the leg 85 4 of the clip 3 and provide for the cutting edge 12 around the same for the purposes hereinafter described.

In constructing the roof *a* in accordance with my invention the supporting bars or 90 channels 2 are placed in position in the usual frame work of the building, and the clips 3 are placed around the upper flanges of the same, with the short legs 5 of such clips fitting under such flanges and the long 95 legs 4 of the same resting on the upper faces of such flanges. When thus in position the clips 3 will be spaced the required distance apart from each other and the shanks 8 on the rivets or staples 7 carried by the same 100 will be held extended or projected upwardly through the holes 6 in legs 4 by reason of the heads 9 on such staples being confined between such legs and the upper flanges on the channel bars 2, so that the headed ends 105 11 on such staples will be in position for attaching the sheets 1 together as hereinafter described.

The sheets 1 are positioned to overlap each other over the upper flanges on the 110

channel bars 2 and are then driven down by hammering the same against the heads 11 on the staples 7 so that such heads will be punched through the two overlapped sheets, 5 after which such heads can be flattened by such hammering to rivet the sheets together and thereby hold the same in place.

It will thus be seen that in the formation of my improved sheet metal roof, the sheets 10 can be firmly attached together and through their overlapping portions, and when so formed, there will be no obstructions in the way of painting the under side of the same, while in constructing such roof only the operator 15 on the roof will be required to connect the sheets together and thereby effect a great saving in labor, as well as also in the material of the device for connecting such sheets together. The attaching device 20 being formed of a single unit can be easily shipped for installation on the roof, and being capable of being connected to and carried by the roof supporting bars will always be in position for instant and ready use, 25 while it also can be used a number of times.

Various modifications and changes in the application, design, construction and combination of parts of my improved device may be resorted to without departing from the spirit of the invention or sacrificing any 30 of its advantages.

What I claim as my invention and desire to secure by Letters Patent is:—

As a new article of manufacture, a roofing clip comprising a metallic strip bent to 35 form a hook portion and a shank portion, the shank portion being longer than the hook portion, said shank portion having a hole therein beyond the end of said hook portion, and a rivet disposed in the hole of 40 said shank portion, said rivet having a head at one end, and being slightly headed at the other end, for the purposes set forth.

In testimony whereof I, the said WILLIAM G. PATRIDIS, have hereunto set my hand.

WILLIAM G. PATRIDIS.
